United States Patent Office.

CHARLES A. BRADFORD AND WESLEY BRADFORD, OF CROWN POINT CENTRE, NEW YORK.

Letters Patent No. 73,772, dated January 28, 1868.

IMPROVEMENT IN REIN-HOLDER.

The Schedule referred to in these Letters Patent and making part of the same.

TO ALL WHOM IT MAY CONCERN:

Be it known that we, CHARLES A. BRADFORD and WESLEY BRADFORD, of Crown Point Centre, in the county of Essex, and State of New York, have invented a new and useful Improvement in Rein-Holders; and we do hereby declare that the following is a full, clear, and exact description thereof, which will enable those skilled in the art to make and use the same, reference being had to the accompanying drawings, forming part of this specification.

This invention relates to an improvement in rein-holders, and consists in a rod or bar, of steel or iron, or other suitable material, surmounted by a cross-piece, having eyes for the reins. A worm on the other end of the rod works into a clamp, by which it is held to the beam of the plough, harrow, or other farming-implement or carriage.

The accompanying drawing is a front view of our improved rein-holder.

Similar letters of reference indicate corresponding parts.

A is a rod, of iron, steel, or other suitable material, surmounted by the cross-piece B, carrying the eyes b, through which the reins are received. A thread, a, at the lower end of A, works into the clamp C, by which the rein-holder is held to the beam of the plough, harrow, or other farming-implement or carriage, or the prolongation of the rod A may form the back and base of the clamp, a cross-piece, c, completing them, through which a thumb-screw may set, to clamp the rein-holder to the beam.

By the use of this rein-holder, the reins are kept from getting under or entangled with the whiffle-trees, when turning round.

We claim as new, and desire to secure by Letters Patent—

The bar A, having the worm a at its lower extremity, in combination with the eyes b and clamp C, in manner substantially as above set forth and described.

The above specification of our invention signed by us, this 19th day of July, 1867.

CHARLES A. BRADFORD,
WESLEY BRADFORD.
